United States Patent Office

Des. 178,556
Patented Aug. 14, 1956

178,556

JUVENILE VEHICLE

Joseph Swbado, Toledo, Ohio

Application April 11, 1956, Serial No. 41,023

Term of patent 14 years

(Cl. D34—15)

Fig. 1

Fig. 2

Figure 1 is a front perspective view of the juvenile vehicle, showing my new design; and

Figure 2 is a side elevation of the juvenile vehicle.

I claim:

The ornamental design for a juvenile vehicle, as shown.
